US00D783400S

(12) **United States Design Patent** (10) **Patent No.:** **US D783,400 S**
Bois (45) **Date of Patent:** **** Apr. 11, 2017**

(54) **CLOSURE FOR CONTAINER**

(71) Applicant: **Clariant Production (France) SAS**,
Trosly Breuil (FR)

(72) Inventor: **Dominique Bois**, Choisy le Roi (FR)

(73) Assignee: **Clariant Production (France) SAS**,
Trosly Breuil (FR)

(**) Term: **14 Years**

(21) Appl. No.: **29/503,018**

(22) Filed: **Sep. 22, 2014**

(30) **Foreign Application Priority Data**

Mar. 21, 2014 (EM) 002429886

(51) **LOC (10) Cl.** **09-07**

(57) **CLAIM**

The ornamental design for a closure for container, as shown and described.

DESCRIPTION

FIG. 1 is a front view of the new design;

FIG. 2 is a rear view of the design of FIG. 1;

FIG. 3 is a side view of the design of FIG. 1;

FIG. 4 is a top view of the design of FIG. 1;

FIG. 5 is a perspective rear view of the design of FIG. 1;

FIG. 6 is a perspective front view of the design of FIG. 1;

FIG. 7 is a side, part cross-sectional, view of the design of FIG. 1; and,

FIG. 8 is a bottom view of the design of FIG. 1.

The broken lines shown in the drawings depict portions of the closure for container that form no part of the claimed design.

1 Claim, 7 Drawing Sheets
